CLOCK

Waldemar Blessing, Waldkirch im Breisgau, Germany,
assignor to Blessing Werke KG, Waldkirch im Breisgau,
Germany

Filed Mar. 31, 1970, Ser. No. 22,133

Claims priority, application Germany Jan. 15, 1970

Term of patent 14 years

Int. Cl. D10—01

U.S. Cl. D42—7

FIG. 1

FIG. 2

FIG. 1 is a perspective view of a clock showing my new design; and

FIG. 2 is a right side elevational view thereof, the left side being substantially a mirror image.

The side of the clock not shown in the drawing has the same appearance as the side shown in FIG. 2.

The rear of the clock is plain.

I claim:

The ornamental design for a clock, substantially as shown and described.
